UNITED STATES PATENT OFFICE.

ALFRED CATCHPOLE, OF GENEVA, NEW YORK.

STEAM OR HOT-WATER RADIATOR.

SPECIFICATION forming part of Letters Patent No. 379,047, dated March 6, 1888.

Application filed May 7, 1887. Serial No. 237,429. (No model.)

To all whom it may concern:

Be it known that I, ALFRED CATCHPOLE, of Geneva, in the county of Ontario, in the State of New York, have invented new and useful 5 Improvements in Steam or Hot-Water Radiators, of which the following, taken in connection with the accompanying drawings, is a full, clear, and exact description.

This invention relates to the class of steam 10 or hot-water radiators which are composed of upright tubes mounted on a steam or water chamber and communicate therewith.

The invention consists, first, in forming the 15 radiator of vertical transverse sections detachably connected to each other, and thus made extensible, as may be required to heat different-sized rooms; secondly, in forming the radiator-tube integral with a section of the bottom chamber, thereby obviating the expense 20 of fitting and securing the tube to the bottom chamber; thirdly, in a novel construction of the radiator-tube and its arrangement in relation to the companion tubes, whereby the radiator is rendered more compact, and at the 25 same time presents increased radiating-surfaces; and the invention furthermore consists in certain novel features of the details of the radiator, all as hereinafter more fully described, and set forth in the claims.

30 In the annexed drawings, Figure 1 is a side elevation of a radiator embodying my improvements. Fig. 2 is an inverted plan view of the same. Fig. 3 is a vertical longitudinal section of a portion of the radiator, taken through the center or on the line $x-x$, Fig. 8. Figs. 4 and 35 5 are vertical transverse sections, respectively, on lines $y-y$, Fig. 7, and $z-z$, Fig. 8. Fig. 6 is a horizontal transverse section on line $U-U$, Fig. 1. Figs. 7 and 8 are enlarged horizontal 40 transverse sections of a steam-radiator tube and a hot-water-radiator tube, respectively. Figs. 9 and 10 are enlarged horizontal longitudinal sections of the bottom chambers of a hot-water radiator and a steam-radiator, respectively; and Fig. 11 is a detached perspective view of a section of my improved radiator.

45 Similar letters of reference indicate corresponding parts.

A represents the bottom chamber of the 50 radiator. When designed for hot water, I provide said chamber with longitudinal partitions

$a-a$, united at one end and forming an eduction-channel, b , between them and an induction-channel, c , around them, as shown in Fig. 9 of the drawings. In a steam-radiator the aforesaid partitions are omitted, as illustrated in Fig. 10 of the drawings. This bottom chamber, A, I divide transversely on the lines $d-d$ and detachably connect the sections to each other by coupling-bolts $e-e$, passing through 60 ears $f-f$, cast on the respective sections, as represented in Fig. 2 of the drawings, and in order to conceal these couplings I provide the sides of the chamber with supporting-flanges $g-g$, which house or cover the said coupling. 65

B represents the radiator-tube, which I form integral with one of the sections of the chamber A, and thus reduce the cost of manufacture, as hereinbefore stated. The tube B, I form of vertical tubular ribs $r-r$, arranged parallel side by side with a space, h , between them and united back of said space and at the top, and the vertical tubular rib r' , projecting rearward from the junction of the ribs $r-r$ and communicating with the same at their upper ends. 70 Each of the tubes B is thus formed integral with a section, C', of a cap, C, extending the length of the radiator, as represented in Fig. 1 of the drawings, said sections being separated from each other by the front and rear 75 walls, $i-i$, of said sections, as shown in Fig. 3 of the drawings. The described radiator-tubes B B, I arrange in such a manner as to cause the rib r' of each tube to project into the space h between the ribs $r-r$ of the adjacent tube, as 80 illustrated in Fig. 6 of the drawings, thereby rendering the radiator more compact. 85

It will be observed that by the described 90 form of the radiator-tube I materially increase the radiating-surface thereof.

In a hot-water radiator I separate the hollow ribs $r-r-r'$ from each other by longitudinal partitions $l-l$, as illustrated in Figs. 4 and 7 of the drawings, which partitions terminate a short distance below the cap C. The tubular ribs $r-r$ communicate at the base with the channels $c-c$ and the tubular rib r' communicates with the eduction-channel b . The hot water is thus made to ascend from the channels $c-c$ of the chamber A through the ribs $r-r$ and pass over 100 the upper ends of the partitions $l-l$, and thence descend through the rib r' to the eduction-

channel *b*, from whence it is conducted back to the heater by a pipe, *n*, connected to said ejection-channel, as illustrated in Fig. 9 of the drawings.

5 Having described my invention, what I claim as new, and desire to secure by Letters Patent, is—

1. A steam or hot-water radiator-tube composed of the vertical tubular ribs *r r*, arranged side by side with the space *h* between them and united back of said space and at the top, the vertical rib *r'*, projecting rearward from the junction of the ribs *r r* and communicating with the same, and the chamber-section *A*, 15 formed integral with the aforesaid tube, substantially as described and shown.

2. In a steam or hot-water radiator, the radiator-tubes, each composed of vertical tubu-

lar ribs arranged parallel side by side with a space between them and united at one of their longitudinal edges, and a vertical tubular rib projecting from the junction of the parallel ribs and communicating with the same at their upper ends and arranged in the space between the parallel ribs of the adjacent radiator-tube, 20 substantially as described and shown.

25 In testimony whereof I have hereunto signed my name and affixed my seal, in the presence of two attesting witnesses, at Geneva, in the county of Ontario, in the State of New York, this 5th day of May, 1887.

ALFRED CATCHPOLE. [L. S.]
